UNITED STATES PATENT OFFICE.

MILAN BOGDANOVIC, OF CLEVELAND, OHIO.

RAIL-JOINT.

1,223,139.

Specification of Letters Patent. Patented Apr. 17, 1917.

Application filed February 18, 1915. Serial No. 9,111.

To all whom it may concern:

Be it known that I, MILAN BOGDANOVIC, a subject of the Emperor of Austria, residing at Cleveland, in the county of Cuyahoga and State of Ohio, have invented certain new and useful Improvements in Rail-Joints, of which the following is a specification.

This invention relates to interlocking features for the meeting ends of metal bars or rails, and is more particularly designed with reference to railway rails, is so illustrated and will be so described.

Assuming, for the purpose of description, that adjacent rails are disposed horizontally, as when in use, the head and foot sections of the meeting ends terminate in vertically or transversely disposed abutments, and the webs have both horizontal or 20 longitudinal and vertical or transverse abutting surfaces.

With this understanding, one object of my invention is to provide the meeting ends of rails with studs and cavities which interlock and hold the abutting surfaces of the two rail sections in close contact. A further object of the invention is to provide the meeting ends of rails with interlocking elements which tend to draw and maintain the 30 abutting surfaces of adjacent rail sections in close contact. A further object of the invention is to provide for the ready disconnection of rail sections or lengths. A further object of the invention is to provide for 35 avoidance of lodgment of moisture at the junction of rail lengths.

With these and minor objects in view, my invention consists in details of construction and combinations which will be hereinafter 40 described, and claimed.

In the accompanying drawings:

Figure 1 is a view in perspective showing the meeting ends of rail sections or lengths disconnected.

Fig. 2 is a view in elevation looking at the side of the meeting ends of two rails sections connected.

Fig. 3 is a vertical longitudinal section of the rail joint shown in Fig. 2.

In the drawings I have shown the opposite or meeting ends A and B of two sections or lengths of standard railway rails, each section, of course, having the conventional head 1, foot 2, and web 3.

In the practice of my invention, the end A of a rail section or length is shaped by

cutting, forging, or otherwise, to form three vertical abutments 4, 5 and 6, one, 4, extending from the tread to the web, the second, 5, from the top of the web to the base or 60 foot, and the third, 6, formed by the end of said base or foot; there being two horizontal bearing surfaces or shoulders 7 and 8, one, 7, formed by the top of the web between the vertical abutments 4 and 5, and 65 the other, 8, formed by the top of the rail foot 2.

The opposite end B of a rail length is shaped oppositely, having three vertical abutments 9, 10, and 11, to contact with the 70 abutments 4, 5 and 6 of the end A of an adjacent rail, and horizontal bearing surfaces 12 and 13 to rest upon the corresponding surfaces or shoulders 7 and 8 of the end A. About midway of the shoulder 7 of the rail 75 end A is an upstanding boss 14 designed to interlock with an elongated cavity 15 in the under surface of the head of the rail end B, said rail-end B being provided with a downwardly projecting elongated boss or 80 stud 16 to engage an elongated slot 17 formed in the rail-base or foot 2.

The boss 14 of the rail-end A is tapered from base to top and the cavity 15 of the rail-end B is correspondingly tapered, 85 whereby upon assembling the two rail-ends, the abutting surfaces 4 and 9 of the rail-heads will be drawn snugly together, and in like manner the stud 16 of the rail-end B and the slot 17 of the rail-end A are tapered, to the end that the several abutting surfaces of the rail-ends will be drawn 90 tightly together when they are joined.

While the wedging action between the boss 14 and cavity 15 and the stud 16 and 95 slot 17 is relied upon to draw and maintain abutments of the rail-ends in close contact, it will be understood that there will be sufficient clearance between these parts to permit the rail-ends to be easily joined or taken 100 apart, the wedging action being exerted by those surfaces of the parts proximate the adjacent abutments.

The purpose of providing a slot 17 instead of a mortise or recess in the rail-foot 105 to receive the stud 16, is to admit of drainage for any moisture that may enter the joint between rail-ends, and from the construction shown it will be noted that to disconnect this lock-joint it is only necessary 110 to raise the end B sufficiently for the stud 16 of the rail-end B to clear the slot 17 of

22
the rail-end A, the wedging boss 14 being of less height than the stud 16 will clear itself from the recess 15 before the lower end of said stud 16 has risen free from the draining slot 17.

5 I claim:
A locking joint for the meeting ends of railway rails comprising three unbroken transverse abutments terminating the head, 10 foot and webs of the rails; longitudinal bearing surfaces extending between said abutments; a longitudinally tapered drainage slot in the foot and a tapered wedging

boss upstanding from the web of one rail adjacent the end; and a longitudinal tapered recess in the head and tapered stud depending from the web of the adjacent rail-end; whereby the longitudinal wedging action will draw the abutments together and insure clearance for drainage through the 20 slot in the rail-foot.

MILAN BOGDANOVIC.
